HINGE FOR OVEN DOORS

Harry V. Glore, Oakland, Calif.

Application June 7, 1933, Serial No. 674,662

5 Claims. (Cl. 126—194)

This invention relates to hinge construction and particularly to a hinge for an oven door.

Small portable cook stoves of the type that may be conveniently placed on the table or shelf 5 and are just large enough to receive one receptacle for toasting, baking, frying or the like are finding public favor. While it is desirable to manufacture such stoves at as low cost as possible, it is necessary that the oven or cooking 10 compartment thereof be provided with an accurately fitting closure in order to prevent unnecessary escape of heat and thus increase the efficiency of the cooking operation.

Die stamping is preferable in the manufacture of the walls and various parts of such stoves but it is found that the formation of an accurately operating hinge on an oven door cannot 15 be formed practically and cheaply by die stamping operations.

It is therefore, the object of the present invention to form an oven door and hinge therefor that will provide a close fitting closure for the cooking compartment of a small stove and in which the metal parts of the door and door frame 20 may be made by simple die stamping operations.

One form of my invention is exemplified in the accompanying drawing and described in detail 25 in the following specification.

In the drawing:

Fig. 1 is a perspective view of a front wall of 30 an oven fitted with an oven door hinged thereto in accordance with my invention.

Fig. 2 is a fragmentary perspective view showing the construction of the oven door.

Fig. 3 is a similar view showing the construction 35 of the door frame.

Fig. 4 is a sectional view taken on the line 40 IV—IV of Fig. 1 with the oven door shown in an opening position.

Fig. 5 is a section taken on the line V—V of Fig. 1.

Referring more particularly to the drawing, the front wall of an oven is shown at 10. This oven wall is preferably made of sheet metal and formed by die stamping. A door opening is formed centrally of the wall 10 and surrounded by a channel shaped frame 11 pressed from the material of which the wall is made. A door 12 is provided for closing the opening surrounded by the frame 11 and is formed with a central depression and a marginal flange 13 so that it fits snugly against the outer surface of the frame. The lower edge of the door is formed with spaced tangs which are curled to form bearings 14 for the reception of a pintle pin 17, and the lower 45 edge of the channel shaped frame 11 is provided

with elongated openings 15 through which the bearings 14 may be inserted. An opening 16 is provided at one end of the frame 11, as shown in Fig. 1, so that when the bearings 14 have been inserted through the openings 15, the pintle pin, 5 which is long enough to extend through all three of the bearings 14, may be passed through them and disposed within the channel shaped frame in the position shown in Figs. 4 and 5.

When assembled as above described, the pintle 10 pin 17 serves to retain the door against separation from the frame and also cooperates with the bearings 14 and frame 11 to form a loosely connected hinge. This hinge being loosely connected permits the door to close against the frame with 15 the abutting surfaces tightly fitted. It does not, however, maintain a tight fit when the door is being opened and closed.

In order to provide an accurately fitting bearing that will maintain the door in proper alignment with the opening as it is opened and closed, the interior of the channel shaped frame 11 along the side thereof that is occupied by the pintle pin is filled with a plastic heat resisting composition designated by the numeral 18 in Figs. 4 20 and 5. This composition is preferably asbestos 25 cement or may be a plaster of Paris composition, or any other suitable material that may be forced into the frame in a plastic state and is capable of setting to provide a hard heat resisting material.

The composition 18 is forced into the frame 30 when the door is in its closed position and therefore surrounds the exposed parts of the pintle 17 when it is in a proper position to form an accurate hinge between the door and the frame. 35 Upon setting, the composition hardens about the pintle pin and therefore forms bearings so that the door may be opened and closed freely and will always upon being closed form a tight seal, preventing unnecessary escape of heat from the 40 oven chamber.

From the foregoing it will appear that I have 45 provided a novel hinge construction which is simple and inexpensive to manufacture but capable of maintaining a door in accurate alignment with the opening that it is intended to close.

While I have shown my invention in its preferred form, it will be understood that various changes may be resorted to in the construction and arrangement of its several parts without varying from the scope of the appended claims.

Having thus described my invention, what I 50 claim and desire to secure by Letters Patent is:

1. A hinge for fastening a door to a frame comprising bearing members formed on the door for the reception of a pintle pin, and a plastic ma- 55

aterial carried by the frame and forming a bearing for the pintle pin.

2. A hinge for fastening a door to a frame comprising bearing members carried by the door for the reception of a pintle pin, said frame having openings through which said bearing members extend, and a plastic composition behind the frame in which the pintle pin is embedded.

3. A hinge for fastening a door to a frame comprising bearing members carried by the door, a pintle pin carried by said bearing members, and a bearing member in the frame consisting of a plastic composition surrounding the pintle pin.

4. A hinge for fastening a door to a frame com-

prising bearing members for a pintle pin on said door, a channel shaped edge on said frame having holes through which said bearing members extend, and a plastic material contained by said channel shaped edge and embedding said pintle pin to form bearings for the pintle pin.

5. A hinge for fastening a door to a frame which comprises a pintle pin supported by the door and lying within the frame, and a plastic compound supported by the frame and forming a bearing and the sole support for said pintle pin with relation to the frame.

HARRY V. GLORE.
